The outer end of the drag-rod *f* is provided with a downwardly projecting beak *v* capable of being engaged by the hooked end *w* of a control latch lever *x* fulcrumed to the loom framework as at *y*.

During normal working of the loom, the heald *a* is moved up and down in conformity with the movements of the shuttles, by the action of the main cam *n* through the medium of lever *k*, drag rod *f*, bell crank lever *c*, *d* and operating rod *b*.

When, however, it is desired to uncover the shuttles, the latch levers *x* are raised and so is the rod *s* (by suitable means not shown) so that the hook *t* will engage with the hooking piece *u*, whereby the lever *k* is drawn backwards beyond the influence of the cam *n* and the heald *a* is moved into its lowermost position under the influence of the auxiliary cam *q*.

The healds *a* are then retained in their extreme lowered positions by the latch levers *x* through the engagement of the beaks *v* with the hooks *w* and so retain the drag rods *f* in their retracted positions. Lowering the latch levers *x* releases the mechanism to the control of the auxiliary cams *q* whereby the healds *a* may be permitted to rise and cover the shuttles at the appropriate times, this being followed by the release of the hooks *t* from the hooking pieces *u* so that normal weaving may proceed under the control of the main cams *n*.

We claim:

1. In a circular loom having healds, a pivoted main rocker lever having a cam for actuating it to move the respective heald in one direction and a spring for moving the heald in the opposite direction, catch means fixed to said rocker lever, a pivoted auxiliary rocker lever having a cam for actuating it, and hook means pivotally connected to the auxiliary rocker lever for movement about its pivot into and out of engagement with said catch means, the auxiliary rocker lever being operative by its cam to turn the main rocker lever about its pivot while said hook means is engaged with said catch means.

2. In a circular loom having healds, a pivoted main rocker lever having a cam for actuating it to move the respective heald in one direction and a spring for moving the heald in the opposite direction, a transversely projecting hooking piece on said rocker lever, an auxiliary rocker lever, a hooked rod pivotally connected to the auxiliary rocker lever and movable about its pivot into and out of engagement with said hooking piece on the main rocker lever, and auxiliary cam means for actuating said auxiliary rocker lever to turn the main rocker lever about its pivot through the medium of said hooked rod and hooking piece.

3. In a circular loom having healds, a pivoted main rocker lever having a cam for actuating it to move the respective heald in one direction and a spring for moving the heald in the opposite direction, a catch means fixed to said rocker lever, an auxiliary rocker lever, hook means pivotally connected to the auxiliary rocker lever and movable about its pivot into and out of engagement with said catch means, auxiliary cam means for actuating the auxiliary rocker lever to turn the main rocker lever about its pivot, additional catch means connected to the main rocker lever, and additional hook means having means for pivotally mounting it on a fixed part of the loom and movable into engagement with the additional catch means connected to the main rocker lever.
